MACHINE FOR GRINDING GEAR TEETH BY
THE GENERATING PROCESSFritz Linse, Chemnitz, Saxony, and Albert Bell-
mann, Glauchau, Saxony, GermanyApplication August 20, 1937, Serial No. 160,188
In Germany September 25, 1936

10 Claims. (Cl. 51—56)

The invention relates to machines for grinding gear teeth by the generating process by means of two flat grinding wheels which are inclined at the flank angle to one another.

5 In the known machines of this kind, the two grinding wheels have been arranged so that their axes were disposed in the same plane perpendicular to the axis of the blank. The wheels have therefore been positioned with their backs inclined at the flank angle and opposite each other. Any other arrangement has been impossible, since the axes of the grinding wheels lay in the same plane. Even if it has been advantageous for both wheels to work simultaneously, the known 10 wheel arrangement was accompanied by a large number of considerable disadvantages. In the first place, in consequence of the lack of space, it has only been possible to make the grinding wheels and also their mounting, grinding wheel 15 spindles and the means of attachment of the grinding wheels to the spindles, of a weak construction. Consequently, it has only been possible to grind off relatively thin chippings with a slight feed. The mounting and the spindles have 20 consequently had to be weak because they could only be arranged on the side of the flat grinding surfaces, the consequence of which has again been that they projected into the rolling space of the blank. If the size of the blank was not to 25 be limited excessively, it has only been possible to attain this at the expense of the mounting and the thickness of the spindles.

30 Truing of the grinding wheels has only been possible in the work pauses, and has had to be avoided as far as possible in order not to increase the machining time unnecessarily. Consequently, the width of the flat annular grinding surfaces has only been made small (2 mm.), since it is known that such narrow grinding edges are 35 self-truing. This slight width of the grinding edge in its turn implies a small feed and therefore reduces the output of the machine.

35 The grinding wheels being situated in the same plane perpendicular to the axis, it has only been possible in the case of coarse pitches to incline them in such a manner that two wheels could be inserted in the same tooth gap. The smaller the pitch, the more gaps and teeth have had to be situated between the simultaneously machined 40 tooth flanks. For example, in the case of the module 2 to 2.35, two teeth and three tooth gaps lie between the machined flanks, and in the case of module 3.5 to 7.5 one tooth and two gaps. Only from the module 8 onwards, has it been 45 possible to insert both grinding wheels in the same gap. Thus, the rolling movement has risen to 7 pitches for module 2.

50 Due to the weakness of the grinding wheels, the weakness of their mounting, of their spindles and their means of attachment to the spindles,

the difficulty of truing and the necessity for a narrow grinding edge, as well as the considerable generating or rolling movement, the output of the known machines has been extremely reduced. An increase in the output would only have been 5 possible by overstraining the machine and hence at the expense of the quality of the grinding obtained.

10 All these disadvantages are obviated by the grinding machines of the invention, which is 10 characterised in that the two grinding wheels are offset relatively to one another in the longitudinal direction of the tooth flanks so that the grinding wheels do not overlap one another. With this arrangement of the grinding wheels, it is possible 15 to take a single tooth between the flat grinding surfaces or to insert both grinding wheels in the same tooth gap, since the wheels may now be inclined so that the planes of their grinding surfaces intersect, this arrangement being possible 20 from module 2 upwards to the coarsest of pitches. Consequently, a further feature of the machine according to the invention is that the grinding wheels grind both flanks of the same tooth or 25 the same gap. Furthermore, according to the invention, the grinding spindles may be situated on the grinding wheel backs opposite the flat grinding surfaces.

30 It follows therefrom that for all occurring teeth, the rolling angle may be reduced to a minimum. Furthermore, the grinding spindles and hence also their mounting and their drives may be situated entirely outside the space necessary for the rolling of the blank, and in fact so high above the imaginary rack for the generation that 35 spindles and mountings may be constructed in a practically rigid manner. Likewise, the limitation regarding the strength of the grinding wheels and the fixing of the wheels on their spindles is eliminated, since the wheels no longer 40 lie opposite each other. In consequence of the strong construction of the wheels, of their fixing means and their mounting, it is possible to work with a thick chipping and considerable feed without endangering the quality of the work. 45 The considerable feed shortens the time of the grinding work for each stroke and the considerable thickness of chippings reduces the number of grinding strokes.

50 In the grinding wheel arrangement according to the invention, the in-feed and truing device of each grinding wheel may be set in operation during the idle running of the wheel. Truing may therefore be carried out as often as desired 55 without loss of time, so that it is possible to dispense with the narrow self-truing grinding edge. The width of the grinding edge on the contrary may be selected in accordance with the feed or vice versa. The possibility of using wide grinding edges likewise permits of a considerable feed. 60

The advantages depicted are so considerable that the apparent disadvantage that the two offset wheels operate successively, so that a larger grinding stroke of the wheels relatively to the blank is necessary, is not only outweighed but a machine according to the invention requires a smaller expenditure of time for each individual grinding stroke, especially since it is possible to shorten the time of the idle path by a quick motion. Thus, there is not only a very considerable saving in time for the individual grinding stroke, but in addition there is the fact that, in consequence of the greater possible thickness of chippings, the number of grinding strokes may be reduced. The capacity of the machine is on the whole at least doubled.

Machines are also known in which grinding wheels having a conical grinding surface are employed. The machine according to the invention, like any machine with flat grinding surfaces, is superior to said known machines in that more accurate grinding is secured (continuously curved tooth profile instead of facet grinding).

A construction of a grinding machine according to the invention is shown by way of example in the accompanying drawings.

Figure 1 is a side view of the grinding machine. Figure 2 is an end view of the machine seen from the indexing head side, with the rolling arc housing removed.

Figure 2a is a view of the rolling arc housing. Figure 3 is an end view of the machine from the driving side.

Figure 4 is a plan of the machine partly in horizontal section half way up the machine.

Figure 5 is a gear diagram of the bevel wheel drive in the oscillating bed of the machine.

Figure 5a is a plan of Figure 5 seen in the direction of the arrow.

Figure 6 shows the grinding wheels in engagement with the blank.

Figure 7 shows diagrammatically the grinding wheels and rack and the development of a wheel therein.

Figure 8 shows diagrammatically the passage of the grinding wheels through the blank.

Figure 8a shows diagrammatically the distance which is bridged over by the quick-motion.

Figure 9 shows diagrammatically the drive of the grinding spindle, the drive of the change-speed gears, and the drive of the in-feed and truing devices.

In the drawings the machine bed is denoted by 1, the gear blank by 2 and the grinding wheels by 3 and 4. The gear blank wheel is carried by a mandrel 5 held by the centres 6 and 7. The centre 6 is connected with the pitch apparatus 8, which may be of any desired construction. Behind the pitch apparatus 8 and likewise connected to the mandrel 5, is the rolling arc 9 which is connected to the pitch apparatus 8 and the blank 2 in any manner which permits these parts to oscillate together without rotating relatively to one another. The division from tooth to tooth is effected independently of the rolling operation. Above the rolling arc 9 there are tensioned steel tapes 10 and 11. These steel tapes are secured externally to a frame 12 and are tensioned by means of tensioning devices 13 and 13a, which in their turn are vertically adjustable. With this arrangement, the pivot 14 of the rolling arc 9 and of the pitch apparatus 8, the centres 6 and 7 and the mandrel 5 move with the gear blank 2 horizontally on a straight line. For taking up the weight of these parts a slide 15 is

provided which is transversely movable in a guide 16 on the machine bed.

The drive of the rolling arc 9 is effected by means of a crank disc 17 and a crank rod 18 engaging the slide 15 at point 19. The drive of the crank disc will be described hereinafter.

On the bed 1 is a standard 20 on which is vertically slidably a slide 21 having a horizontal slideway 22 situated in the longitudinal direction of the machine. In the slide way 22 is a slide 23 from which are slidably suspended the bearing brackets 24 and 25. Furthermore the slide 23 carries the housings 26 and 27 for the drive of the grinding wheel in-feed and truing devices and the driving motors 28 and 29 for the 15 grinding wheels 3 and 4 and the in-feed and truing devices.

Rotatably and fixably mounted on the bearing brackets 24 and 25 are the grinding headstocks 30 and 31 with the in-feed and truing devices for 20 the grinding spindles 32 and 33.

Belt drives 34 and 35 are provided for driving the grinding spindles and the in-feed and truing elements. Connection between the in-feed and truing devices in the headstocks 30 and 31 and 25 the drive housings 26 and 27 is effected by means of articulated shafts which, however, are not shown in the figures.

A fuller description of the control of the in-feed and truing device driving gears is not necessary in the present application.

The slide 23 is adapted to reciprocate in the longitudinal direction of the tooth flanks. It carries two transverse guideways 36 and 37 in which the bearing brackets 24 and 25 are slidably guided for adjusting the grinding wheels 3 and 4 in accordance with the tooth pitch. The main driving motor 38 is accommodated in the interior of the machine bed. From it a belt 39 leads upward to a belt pulley 40 on a shaft 41 which extends into the main gear box, in the interior of which are accommodated all the pinion and control elements for the rolling movement, for driving the pitch device, driving the grinding spindle slide and for the feed and quick-motion thereof.

Above on the main gear box 42 is a longitudinal slide 43 which receives its reciprocatory movement from the main gear box, through a rack 43' mounted on the underside of the slide 43 and 50 meshing with a driving gear 43" in the gear box which in turn is alternately driven in opposite directions from the main shaft 41, through conventional control and transmission means (not shown), as will be readily understood by those skilled in the art. The movements of this slide are transmitted by a vertical stationary shaft 44 and by wheels 45 and 46 in conjunction with the racks 47 and 48 to the grinding spindle slide 23. Furthermore, mounted on the longitudinal slides 60 43 are longitudinally slidable stops 49 for controlling all the gear elements in the main gear box. As shown in Fig. 1, the stops 49 are pivotally mounted to carry out a switching movement that is transmitted to the driving and control 65 mechanism in the gear box through the rotation of the pivots of the stops. A fuller description of this control is also unnecessary in the present application.

In the position shown in Figure 4, the machine 70 according to the invention serves for the production of spur wheels. For grinding helical wheels, the rolling slide guide 16 with the rolling slide 15 and the rolling tape housing 12 are oscillated about a vertical axis 50 in accordance with the 75

angle of tooth obliquity of the gear blank to be machined. For this purpose, the machine bed 1 carries an arcuate slideway 51 for an oscillating bed 52 carrying the rolling slide 15 and the rolling tape housing 12. In addition, the oscillating bed 52 is provided with a guideway 53 in which the rolling arc housing 12 is slidably and fixably guided in order to be able to effect an angular adjustment of the gear blank 2 by means of the 10 rolling arc 9 and the rolling tapes 10, 11.

Extending from the main gear box 42 is a shaft 54 which by means of the bevel gear pairs 55 and 56 in combination with a gear train, not shown in the figures, drives the crank disc 17 for driving 15 the rolling slide 15.

In shaft 54 there also lies a second shaft and this shaft, by means of the bevel gear pairs 57 and 58 and a further gear train, which is likewise not shown in the figures, serves for driving the 20 pitch apparatus 8. A fuller description of the indexing or pitch operation is again unnecessary in the scope of the application.

It will now be pointed out that in all cases, further indexing from tooth to tooth is effected 25 by the gear blank after each passage of the grinding wheels in the longitudinal direction of the tooth flanks.

Figures 6, 7 and 8 serve to explain the theoretical principle of the machine. Figure 6 shows 30 the grinding wheels 3 and 4 in engagement with a tooth of the gear blank 2, the flat plane surfaces 59 and 60 of the grinding wheels representing the tooth gap of a rack. It does not require any further explanation to see that during the rolling 35 of the blank, the effective surfaces of the grinding wheels must produce involute curves.

Figure 7 shows the flat plane surfaces 59 and 40 60 of the grinding wheels placed in an imaginary rack 61 and the corresponding gear blank 2 in the end positions of the rolling movement. In this figure, A is the rolling path which is necessary for rolling a tooth of the gear blank on the grinding surfaces of the tool.

Figure 8 shows the relative positions of the 45 grinding wheels and gear blank during machining. Only one tooth 62 of the gear blank is shown in longitudinal section. The grinding wheels 3 and 4, before each working stroke, are situated either in the position shown entirely on the right 50 or entirely on the left. Assuming that the wheels start from the right-hand position, then the wheel 3 will first run along one flank of the tooth 62 which is rolling to and fro. Figure 8a shows the position of the grinding wheels 3 and 55 4 relatively to the single tooth 62 after the grinding wheel 3 has run completely through the tooth. The approach of the grinding wheel 4 to the tooth is effected by quick-motion, whereupon the passage of the wheel 4 along the other flank of 60 the same tooth is completed. After the wheel 4 has completely passed through the gear blank, the further indexing movement of the gear by one tooth is effected and the cycle described is completed again in the opposite direction. In Figure 65 8, B is the total path which the grinding slide 23 has to make in this case. In Figure 8a, C is the path which is travelled in the quick-motion of the grinding slide. In Figures 8 and 8a, the constant grinding wheel distance is D and the 70 tooth to be ground is E. It requires no further explanation to see that an increase of E effects a reduction in D. As already stated, while one grinding wheel is in the working position, the other grinding wheel may be automatically trued 75 and vice versa. Since, therefore, no special work-

ing time is employed for truing the grinding wheels, the truing of the wheels, as already mentioned, may be effected as often as desired without loss of time.

A truing device is indicated diagrammatically 5 in Figure 6. Mounted on the grinding headstocks 30 and 31 are pins 63 and 64, respectively, carrying the rocking arms 66 and 65, on the free ends whereof are the truing diamonds. These arms, as indicated in Figure 8, having the same 10 spacing as wheels 3 and 4, and are adapted to be swung to and fro automatically over the width b of the edge of the grinding wheels 3 and 4 to true the wheels on each stroke away from the work gear. Swinging is effected in any known 15 manner by means of the control mechanisms accommodated in the grinding headstocks 30 and 31. The control of the mechanisms is effected by means of adjustable stops 67 on the horizontal slideway 22. As shown in Fig. 1, the stop 67 is 20 pivotally mounted to carry out a switching movement that is transmitted to the driving and control mechanism in the gear box through the rotation of the pivot of the stop. The skilled person has sufficient mechanisms available for this purpose. 25

Figure 9 shows diagrammatically the combined drive for the grinding spindles and for the index and truing devices seen in plan.

We claim:

1. In a machine for grinding gear teeth by the generating method, means for rolling the roughed out blank as on a basic rack, means for reciprocating the grinding wheels longitudinally of the gear teeth, said reciprocating means comprising a slide at the top of the machine above the blank adjustable up and down and movable to and fro longitudinally of the gear teeth, a pair of independently slidable cross slides hanging downward therefrom, grinding wheels having a flat 40 grinding face carried by said cross slides, the grinding faces of said wheels being at the flank angle of the teeth of said basic rack, said grinding wheels being offset longitudinally of the gear teeth to be displaced in their projections by a 45 substantially constant amount, and means for feeding the grinding wheels in a crosswise direction.

2. In a machine for grinding the working surfaces of the teeth of gear wheels, a tool unit comprising a pair of grinding wheels each having a planar operative grinding face, means for rotatably supporting said grinding wheels in spaced relationship at a distance between their axes amounting at least to the maximum diameter of one of 50 said grinding wheels, and with the planar grinding faces inclined at the flank angles of two consecutive tooth flanks of a rack mateable with the gear teeth to be ground, a work gear holder, means to reciprocate said tool unit relative to said 55 work gear holder to bring said grinding wheels into successive engagement with a gear wheel, and means to roll the work gear with its pitch line on the grinding wheels.

3. In a machine for grinding the working surfaces of the teeth of gear wheels, a tool unit comprising a pair of grinding wheels each having a planar operative grinding face, means for rotatably supporting said grinding wheels in spaced relationship with a distance between their axes 70 which is substantially constant during operation and amounts at least to the maximum diameter of one of said grinding wheels, and with their planar grinding faces inclined at the flank angles of two consecutive tooth flanks of a rack mateable 75

- with the gear teeth to be ground with the angle between the grinding wheel axes directed with its vertex towards the work gear, a work gear holder, means to reciprocate said tool unit relative to said work gear holder to bring said grinding wheels into successive engagement with a gear wheel, and means to roll the work gear with its pitch line on the grinding wheels.

4. In a machine for grinding the working surfaces of the teeth of gear wheels, a tool unit comprising a pair of grinding wheels each having a planar operative grinding face of considerable radial extension, means for rotatably supporting said grinding wheels in spaced relationship at a distance between their axes which is substantially constant during operation and amounts at least to the maximum diameter of one of said grinding wheels, and with their planar grinding faces inclined at the flank angles of two consecutive tooth flanks of a rack mateable with the gear teeth to be ground, a work gear holder, means to reciprocate said tool unit relative to said work gear holder to bring said grinding wheels into successive engagement with a gear wheel, and means to roll the work gear with its pitch line on said grinding wheels.

5. In a machine for grinding the working surfaces of the teeth of gear wheels, a tool unit comprising a pair of grinding wheels each having a planar operative grinding face, means for rotatably supporting said grinding wheels in spaced relationship with a distance between their axes of not less than the maximum diameter of one of said grinding wheels, and with their planar grinding faces inclined at the flank angles of the two flanks of a tooth of a rack mateable with the gear teeth to be ground, a work gear holder, means to reciprocate said tool unit relative to said work gear holder to bring said grinding wheels into successive engagement with a gear wheel, and means to roll the work gear with its pitch line on said grinding wheels.

6. In a machine for grinding the working surfaces of the teeth of gear wheels, a tool unit comprising a pair of grinding wheels each having a planar operative grinding face, a spindle extending from each grinding wheel from the side opposite said operative face, means for rotatably supporting said spindles in spaced relationship with a distance between their axes which is substantially constant during operation and amounts at least to the maximum diameter of one of said grinding wheels, and with the planar grinding faces inclined at the flank angles of two consecutive tooth flanks of a rack mateable with the gear teeth to be ground, a work gear holder, means to reciprocate said tool unit relative to said work gear holder to bring said grinding wheels into successive engagement with a gear wheel, and means to roll the work gear with its pitch line on said grinding wheels.

7. In a machine for grinding the working surfaces of the teeth of gear wheels, a tool unit comprising a pair of grinding wheels each having a planar operative grinding face, means for rotatably supporting said grinding wheels in spaced relationship with a distance between their axes which is substantially constant during operation and amounts at least to the maximum diameter of one of said grinding wheels, and with their planar grinding faces inclined at the flank angles of two consecutive tooth flanks of a rack mateable with the gear teeth to be ground, a work gear holder, means to reciprocate said tool unit relative to said work gear holder to bring said grinding wheels into successive engagement with a gear wheel, and means to roll the work gear with its pitch line on said grinding wheels.

8. In a machine for grinding the working surfaces of the teeth of gear wheels, a tool unit comprising a pair of grinding wheels each having a planar operative grinding face, means for rotatably supporting said grinding wheels in spaced relationship with a distance between their axes which is substantially constant during operation and amounts at least to the maximum diameter of one of said grinding wheels, and with their planar grinding faces inclined at the flank angles of two consecutive tooth flanks of a rack mateable with the gear teeth to be ground, a work gear holder, means to reciprocate said tool unit relative to said work gear holder to bring said grinding wheels into successive engagement with a gear wheel, and means to roll the work gear with its pitch line on said grinding wheels.

9. In a machine for grinding the working surfaces of the teeth of gear wheels, a tool unit comprising vertically adjustable slide means, a pair of grinding wheels each having a planar operative grinding face, means for rotatably supporting said grinding wheels in depending adjustable position upon said slide means in spaced relationship with a distance between their axes which is substantially constant during operation and amounts at least to the maximum diameter of one of said grinding wheels, and with their planar grinding faces inclined at the flank angles of two consecutive tooth flanks of a rack mateable with the gear teeth to be ground, a work gear holder, means to reciprocate said tool unit relative to said work gear holder to bring said grinding wheels into successive engagement with a gear wheel, and means to roll the work gear with its pitch line on said grinding wheels.

10. In a machine for grinding the working surfaces of the teeth of gear wheels, a machine frame, a tool unit comprising vertically adjustable slide means, a pair of grinding wheels each having a planar operative grinding face, means for rotatably supporting said grinding wheels in depending adjustable position upon said slide means in spaced relationship with a distance between their axes which is substantially constant during operation and amounts at least to the maximum diameter of one of said grinding wheels, and with their planar grinding faces inclined at the flank angles of two consecutive tooth flanks of a rack mateable with the gear teeth to be ground, a work gear holder, means to reciprocate said tool unit relative to said work gear holder to bring said grinding wheels into successive engagement with a gear wheel, a second slide mounted for movement in the reciprocating direction of said tool unit, means including a rack and pinion drive and a shaft mounted with its axis in a vertical, stationary position, for transmitting the movement of said second slide upon said first slide means, and means to roll the work gear with its pitch line on said grinding wheels.

FRITZ LINSE.
ALBERT BELLMANN.
